Primary Examiner — John Windmuller*(74) Attorney, Agent, or Firm* — Sheridan Ross P.C.(57) **CLAIM**

The ornamental design for an RFID tag, as shown and described.

DESCRIPTION

FIG. 1 is a perspective view of an RFID tag;
FIG. 2 is a top plan view thereof;
FIG. 3 is a left side elevational view thereof, the right side elevational view is identical but symmetrically reversed;
FIG. 4 is a bottom plan view thereof;
FIG. 5 is a front elevational view thereof; and,
FIG. 6 is a back elevational view thereof.
The portions of the RFID tag illustrated in broken lines form no part of the claimed design.
